CONTROL APPARATUS

Ralph T. Whitney, Irwin, Pa., assignor to Westinghouse Air Brake Company, a corporation of Pennsylvania

Application May 30, 1945, Serial No. 596,765

8 Claims. (Cl. 123—41)

1

This invention relates to control apparatus and more particularly to a fluid pressure control apparatus for controlling, in a desired sequence, a plurality of different operations, such for example, as operations incident to controlling the operation of a reversible internal combustion engine.

In Patent No. 2,395,202, issued to Roy R. Stevens and Eric G. Erson, on February 19, 1946, there is disclosed a fluid pressure control apparatus which is operable automatically to control the starting, stopping and reversing of an internal combustion engine in response to appropriate operations of a manual controller. In reversing the engine the apparatus operates automatically to first cut off the supply of fuel to the engine, to then reverse the valve timing or valve gear of the engine to provide for operation of the engine in the reverse direction, to next supply starting air to the engine for causing it to start turning in the new direction, following which fuel is supplied to the engine to cause it to run in the new direction.

The principal object of the invention is to provide an improved control apparatus of the above general type.

Other objects and advantages will be apparent from the following more detailed description of the invention.

In the accompanying drawing: Fig. 1 is a diagrammatic view, partly in section and partly in outline, of a control apparatus embodying the invention; Fig. 2 is a partial plan view of an operator's control valve device shown in vertical section in Fig. 1; Figs. 3 and 4 are sectional views taken on the lines 3—3 and 4—4, respectively, in Fig. 1; and Fig. 5 is a sectional view, on an enlarged scale, of a directional control device shown in side elevation in Fig. 1 and taken on a line 5—5 therein.

Description

In the drawing the reference numeral 1 indicates a portion of one end of a crank shaft of a reversible internal combustion engine, and reference numeral 2 indicates a portion of one end of a cam shaft for said engine. The cam shaft 2 may be driven in proper phase with the crank shaft 1 by meshing gears 3 and 4 for operating conventional starting valve mechanisms and fuel injection mechanisms (not shown) in a well known manner to permit the engine to be started by compressed air in either direction of rotation to, for instance, drive a ship either ahead or astern. To provide for the different directions of operation, the cam shaft may be of the longitudinally

shiftable type having a forward position to provide for operation of the engine in the one direction and a reverse position to provide for operation of the engine in the opposite direction. In the drawing the cam shaft is shown in the reverse position and may be shifted by a lever 5 from this position to the forward position in which said lever may occupy a position such as indicated by a dot and dash line 5a.

10 The reference numeral 6 indicates a fuel control shaft for the engine and reference numeral 7 indicates an operating lever for said shaft. The lever 7 and shaft 6 may have a fuel cut-off position in which they are shown in the drawing for
15 cutting off the supply of fuel to the engine to stop same, and may be adjustable out of said position to a position such as indicated by a dot and dash line 8 or to even a greater extent to supply fuel to the engine.

20 A fuel cut-off device 10 is provided for controlling the positioning of the fuel control lever 7. This device comprises a casing containing a piston 11 having at one side a pressure chamber

12 open to a control pipe 13 and having at the
25 opposite side a non-pressure chamber 14. Projecting from piston 11 through the non-pressure chamber 14 is a piston rod 15 which may be provided at its end with a slot in which there is disposed a pin 16 provided in the fuel cut-off lever 1.

30 The non-pressure chamber 14 contains a spring 17 which encircles the rod 15 and acts on the piston 11 for urging same in the direction of the left hand away from a stop shoulder 18. Movement of piston 11 in the direction of the left hand is arranged to be limited by contact between the piston 11 and a stop 19. Upon supply of fluid under pressure to pressure chamber 12 the force created on piston 11 will cause the piston 11 to move the fuel cut-off lever 7 to its fuel cut-off

35

40 position in which it is shown in the drawing. Upon release of fluid under pressure from chamber 12 the spring 11 will move the piston into contact with stop 19 and this movement transmitted through the piston rod 15 will turn or 45 permit movement of the fuel control lever 7 from the fuel cut-off position to the position indicated by the dot and dash line 8 for supplying fuel to the engine.

The reference numeral 22 indicates a starting air valve device arranged to operate upon supply of fluid under pressure to a control pipe 23 for supplying starting air from a starting air supply pipe 24 to a pipe 25 which may convey the air to the starting valves (not shown) of the engine 55 for supply to the engine cylinders (not shown) to

place the engine in motion in the direction determined by the position of the cam shaft 2.

The starting air valve device 22 comprises a supply valve 26 arranged to control communication between pipes 24 and 25, a release valve 27 for controlling communication between pipe 25 and an atmospheric port 28, and a piston 29 for controlling said valves. At one side of piston 29 is a chamber 30 open to pipe 23, and at the opposite side is a chamber 31 open to atmosphere through port 28 and containing a spring 32 under pressure acting on said piston. In operation, when fluid under pressure is supplied to pipe 23, in a manner which will be later described, such pressure will become effective in chamber 30 and actuate piston 29 to close valve 27 and open valve 26 to thereby supply starting air from pipe 24 to pipe 25 for starting the engine. When fluid is released from pipe 23 and thus from chamber 30, spring 32 will return piston 29 to the position in which it is shown in the drawing to thereby open valve 27 and to permit closure of valve 26 by a spring 33, so as to cut off the supply of starting air to pipe 25 and to release air from said pipe to atmosphere. The control of the supply and release of fluid under pressure to and from pipe 23 will be hereinafter described.

A fluid reversing motor 35 is provided for shifting the cam shaft 2 to its two different positions above described. This motor comprises a cylinder 36 containing a power piston 37 which is operatively connected through a piston rod 38 and a link 39 to the free end of the cam shaft shifting lever 5. At one side of the power piston 37 there is provided a pressure chamber 40 while at the opposite side is another pressure chamber 41. Upon supply of fluid under pressure to chamber 40, when fluid under pressure is released from chamber 41, the piston 37 will be moved to the position in which it is shown in the drawing for operating lever 5 to move the cam shaft 2 to its astern position in which it also is shown in the drawing. On the other hand, if fluid under pressure is supplied to chamber 41 when fluid is released from chamber 40, the piston 37 will move to the opposite or right hand end of cylinder 36 to thereby actuate lever 5 to move the cam shaft 2 to its ahead position in which the lever will occupy the position indicated by the dot and dash line 5a.

The supply and release of fluid under pressure to and from chambers 40 and 41 is adapted to be controlled through, respectively, astern and ahead pipes 43 and 44 which connect said chambers to a directional interlock device 45. Reference numerals 45 and 47 indicate respectively astern and ahead control pipes which connect the directional control valve device 45 to an operator's control valve device 48.

The reference numeral 49 indicates a double check valve subject on opposite ends to pressure of fluid in the ahead and astern pipes 44 and 43 respectively, and which is arranged to control communication between said pipes and a third pipe 50 leading to one end of another double check valve 51. When fluid under pressure is supplied to pipe 43, as will hereinafter be described, such pressure, effective on the right hand end of the double check valve 49, will shift said check valve to the position shown in the drawing for opening pipe 50 to pipe 43 and for closing communication between pipe 50 and pipe 44. On the other hand if fluid is supplied to pipe 44 when pipe 43 is vented, the double check valve 49 will move to an opposite position for closing communication be-

tween pipes 50 and 43 and for opening pipe 50 to pipe 44.

The opposite end of the double check valve 51 is subject to pressure of fluid in a pipe 52 which leads to the operator's control valve device 48, and said check valve is arranged to control communication between the pipes 50 and 52 and pipe 13 leading to pressure chamber 12 in the fuel cut off device 10. As will be apparent, if fluid under pressure is supplied to pipe 52, when fluid is released from pipe 50, the double check valve 51 will disconnect pipe 13 from pipe 50 and connect pipe 13 to pipe 52, while if fluid under pressure is supplied to pipe 50 when pipe 52 is vented the double check valve 51 will move to its opposite position for opening pipe 13 to pipe 50 and in which pipe 13 will be disconnected from pipe 52.

The directional control device 45, as shown in detail in Fig. 5, comprises a casing containing an astern interlock valve device 55 and an ahead interlock valve device 53. The two valve devices 55 and 53 are identical in structure each comprising a supply valve 57 contained in a chamber 58 and arranged to control communication between said chamber and a chamber 59. A spring 60 in chamber 58 acts on the supply valve 57 for urging it to its seated or closed position. Each supply valve 57 is provided with a stem 61 extending through chamber 59 and connecting said valve 30 to a plunger 62 provided at the opposite end of the stem. It will be noted that chamber 59 in each of the valve devices 55, 56 encircles the stem 61, and that the plunger 62 is mounted to slide in a bore constituting an extension of said chamber. The chamber 59 is therefore arranged at one side of plunger 62 while at the opposite side is a chamber 63 which is in constant communication with atmosphere through a port 64. A release valve 65 contained in chamber 63 is arranged to seat against the end of plunger 62 for closing communication between said chamber and an axial bore 66 extending through said plunger and the stem 61 and supply valve 57 and opening to the supply valve chamber 58. Each release valve 65 is carried by a stem 67 which extends through a bore in the casing to the exterior thereof.

The two release valve stems 67 are disposed at opposite sides of a pin 68 which is carried in a lug 69 depending from the casing. A lever 70 is fulcrumed on pin 68 and is provided with two oppositely arranged arms 71, one disposed over the end of each of the release valve stems 67 for engagement therewith. The lever 70 is also provided with a third arm 72, the end of which is loosely accommodated in a slot 73 provided in and open to the periphery of a friction disc 74. This disc is carried on one end of a plunger 75 (Fig. 1) which is slidably mounted in a bore provided in a casing 76 which is rigidly supported with respect to the engine so as to support the friction disc in coaxial relation with the end of the engine crank shaft 1. The plunger 75 is also effective in the capacity of a piston for moving the friction disc into frictional contact with the end of the crank shaft 1, and to effect such movement there is provided at its inner end a pressure chamber 77 which is open to the starting control pipe 23.

Rotation of the engine crank shaft 1 and thereby of the friction disc 74 in a counterclockwise or astern direction as indicated by the legend "Astern" in Fig. 5 of the drawing, will rock the lever 70 about the fulcrum pin 68 in a clockwise direction to thereby move the left hand lever arm 71 into contact with the release valve stem

67 in the interlock valve device 55. Further movement of said lever arm will then act to seat the release valve 65 in the interlock valve device 55 against the respective plunger 62 for closing communication between chamber 58 and chamber 63. Further movement of the lever 70 in a clockwise direction will then act through the release valve 65 in the interlock valve device 55 to shift the plunger 62 and open the respective supply valve 57 so as to establish communication between chambers 59 and 58. When the interlock valve device 55 is operated as just described, the parts of the interlock valve device 56 will assume the position in which they are shown in the drawing and in which the respective supply valve 57 is closed and the respective release valve 65 is open. If the crank shaft 1 and disc 74 are turned in the opposite or ahead direction as indicated by the legend "Ahead" in Fig. 5, the lever 70 will be rocked in a counterclockwise direction to thereby effect operation of the interlock valve device 56 to close communication between the respective chambers 58 and 63 and to open said chamber 58 to the respective chamber 59, while in the interlock valve device 55 the respective supply valve 57 will be closed and the release valve 65 open.

A spring 79 having one end connected to a pin 80 secured in the lug 69 above the fulcrum pin 68 has its opposite end connected to a pin 81 secured in the end of lever 72. In the position in which lever 72 is shown in the drawing the line of action of spring 79 is at one side of the axis of pin 68 while in the opposite position of said lever, above described, the line of action of spring 79 will be at the opposite side of the axis of pin 68. This spring is under tension and its purpose is to resiliently hold the lever 70 either in the position in which it is shown in the drawing or in its opposite position after movement by disc 74.

In the astern interlock valve device 55 chamber 58 is connected to pipe 44 and chamber 59 is connected to pipe 47, while in the ahead interlock valve device 56 chambers 58 and 59 are connected, respectively, to pipes 43 and 46.

The operator's control valve device 48 comprises a body 83 and a cover 84 mounted on said body. In body 83 there are disposed what may be called an ahead valve device 85 and an astern valve device 86 for controlling operation of the reversing motor 36 to select the direction of operation of the engine. The body 83 also contains a start valve device 87 for controlling operation of the starting air valve device 22 and the directional control valve device 45, and a stop valve device 88 for controlling operation of the fuel cut-off device to effect stopping of the engine when desired.

The ahead and astern valve devices 85 and 86 and the stop valve device 88 are arranged in spaced parallel relation with their axes shown diagrammatically in the same plane, while the start valve device 87 is arranged with its axis also in said plane but at right angles to the axes of the other valve devices.

All of the valve devices 85, 86, 87 and 88 may be identical in construction, each comprising a fluid pressure supply valve 90 contained in a chamber 91 and arranged to control communication between said chamber and a chamber 92 through an opening encircled by a seat provided for engagement by said valve to close said communication. A spring 93 in chamber 91 acts on valve 90 for urging it into contact with its seat. The valve 90 is connected by a stem 94 which

loosely extends through the valve seat to a plunger 95 which is slidably mounted in a suitable bore in the body, said plunger being of substantially the same area as the seat of valve 90 and subject on one face to pressure of fluid in chamber 92 and on the opposite face to atmospheric pressure in a chamber 96 which is open to atmosphere by way of a passage 97. The valve 90, stem 94 and plunger 95 are provided with an axial bore 98 open at one end to chamber 91, and a release valve 99 disposed in chamber 96 is arranged to control communication between the opposite end of said bore and the latter chamber. The release valve 99 is provided with a plunger 100 extending to the exterior of the body.

The chamber 92 in all of the valve devices 85, 86, 87 and 88 is connected directly to a fluid pressure supply reservoir 101 and thus arranged to be constantly supplied with fluid under pressure when the system is in use. Chamber 91 in the ahead and astern valve devices 85 and 86 are connected respectively to pipes 47 and 46 leading to the directional control device 45. Chamber 91 in the start valve device 87 is connected to a starting control pipe 102, while chamber 91 in the stop valve device 88 is connected to pipe 52 leading to the one end of the double check valve 51.

Disposed over plunger 100 in the valve devices 85, 86, and 88 in the same vertical plane but at right angles to the axes of said plungers is a horizontally disposed hollow control shaft 103 which is suitably journaled at its opposite ends in the cover 84. A plunger 104 is slidably mounted in the control shaft 103 with the left hand end projecting outwardly beyond the adjacent end of said control shaft above plunger 100 of the start valve device 87. A hollow cam shaft 105 is telescoped over and secured to the control shaft 103 and bears at opposite ends against the cover 84 for holding both shafts against axial movement.

The two shafts 103 and 105 are provided with aligned longitudinally extending slots, and the plunger 104 is provided with a like slot and through these slots extends the lower end portion 106 of an operator's control lever 107 which is pivotally mounted on a pin 108 carried by a lug 109 projecting upwardly from the cam shaft 105. In the lower end of portion 106 of the operator's control lever is a slot 110 within which is disposed a transversely extending pin 111 which is secured to plunger 104. It will be seen that rocking of the operator's control lever 107 about the pin 108 in a direction longitudinally of the cam shaft 105 will shift the plunger 104 lengthwise within the control shaft 103, while movement of said lever in a direction about the axis of said cam shaft will rotate said cam shaft without effecting endwise movement of plunger 104.

The operator's control lever 107 extends through a guide slot in cover 84 which provides a definite path of movement of said lever. This slot is shown in plan in Fig. 2 of the drawing and comprises a main portion 112 arranged to permit movement of lever 107 in the direction circumferentially of the cam shaft 105. One end of slot 112 opens to a short slot 113 arranged at right angles to the slot 112, while at the opposite end of slot 112 is another short slot 114 extending in the same direction and parallel to slot 113. The slots 113 and 114 provide for movement of the operator's control lever 107 about the fulcrum pin 108 for moving the plunger 104 outwardly and inwardly of the control shaft 103.

The operator's control lever 107 has five different operating positions in the slots 112, 113 and

114 including a "Stop" position intermediate the ends of slot 112, in which position said lever is shown in Fig. 2 of the drawing. At the end of slot 112 adjacent the short slot 113 the lever has a "Run" position, while at the opposite end of slot 112 said lever has another "Run" position, and at the outer end of each of the slots 113 and 114 said lever has a "Start" position. These positions are indicated in Fig. 2 by appropriate legends, and it will be noted that beyond the short slot 113 is the legend "Ahead," while beyond the short slot 114 is the legend "Astern," which indicate the different directions of engine operation. The "Start" positions in slots 113 and 114 are for starting the engine in the ahead direction or the astern direction, respectively, while the adjacent "Run" position is that in which the operator's control lever will be carried while the engine is running after being started, as will be herein-after described in greater detail.

The body 83 of the operator's control valve device has an exterior lug 116 disposed between plunger 100 of the start valve device 87 and plunger 104 which is slidably mounted in the control shaft 103. A lever 117 fulcrumed intermediate its ends on a pin 118 carried by the lug 116 has one end in contact with stem 100 of the release valve 99 in the start valve device 87, while its opposite end is operatively connected to the projecting end of plunger 104. With the operator's control lever in slot 112, lever 117 and the parts of the start control valve device 87 will occupy the positions in which they are shown in the drawing, in which the start control pipe 102 is open to atmosphere past the respective release valve 99. Movement of lever 107 into either one of the short slots 113 or 114 will however operate plunger 104 and lever 117 to first seat the release valve 99 and then open the supply valve 90 in the start valve device 87 for thereby supplying fluid under pressure from chamber 92 to the start control pipe 102.

The cam shaft 105 is provided with three cams 120, 121 and 122, the peripheral surfaces of which are arranged to contact plungers 100 of the valve devices 85, 86 and 88, respectively, for controlling operation of said devices. The cams 120 and 121 are of identical structure but are reversely arranged on the cam shaft 105. The cam 120 is so designed as to effect closure of the release valve 99 and opening of the supply valve 90 in the ahead valve device 85 when the operator's control lever 107 is in the "Ahead" "Run" and "Start" positions and to permit closing of said supply valve and opening of said release valve in all other positions of said lever. The cam 121 is operative to close the release valve 99 and to open the supply valve 90 in the astern valve device 86 in the "Astern" "Run" and "Start" positions of lever 107 and to permit closure of said supply valve and opening of said release valve in all other positions of said lever. The cam 122 is so designed as to effect closure of the release valve 99 and opening of the supply valve 90 in the stop valve device 88 only in the "Stop" position of the operator's control lever 107 and therefore to permit closure of said supply valve and opening of said release valve in all other positions of said lever.

Pipe 102 connected to the start valve device 87 leads to a reversing interlock valve device 126 which comprises a casing 127 mounted on a housing 128 which is secured to one end of the reversing motor 35. The piston rod 38 extends

through the housing 128 and is supported in a bore through the outer end of said housing.

The casing of the reversing interlock valve device 126 has a chamber 129 connected to the starting pipe 23, and a chamber 130 connected to pipe 102 leading to the start valve device 87 in the operator's control valve device. The chamber 129 contains a supply valve 131 arranged to control communication between chambers 129 and 130 and a spring 132 which acts on said valve for urging it to its closed position. The supply valve 131 is provided with a stem 133 freely extending through a bore in the casing connecting chambers 129 and 130, and into chamber 130 wherein it is connected to one end of a plunger 134 which is slidably mounted in the casing. At the opposite end of plunger 134 is a chamber 135 which is open to atmosphere through a port 136 and which contains a release valve 137 arranged to engage the end of said plunger for closing communication between chamber 135 and a bore 138 which extends through said plunger, the stem 133 and the supply valve 131 to chamber 129.

25 The housing 128 is provided at one side of the piston rod 38 with a bore in which is slidably mounted a ball 139 having contact with the peripheral surface of said rod. Engaging the opposite side of ball 139 is one end of a plunger 140 which is slidably mounted in the bore in the housing, while engaging the opposite side of said plunger is a stem 141 projecting from the release valve 137. The piston rod 38 is provided with a slot 142 arranged to receive the ball 139 to permit movement thereof and of plunger 140 and of the release valve 137 in a direction away from plunger 134 to permit unseating of said valve from said plunger with the supply valve 131 in contact with its seat under pressure of spring 132. The slot 142 is of such length as to displace the ball 139 out of said slot in both extreme positions of the power piston 37 but to permit movement of the ball into said slot in all positions of said piston between said extreme positions. With the ball 139 displaced out of slot 142 it is adapted to seat the release valve 137 against the plunger 134 and to move said plunger to a position in which the supply valve 131 will be opened.

Operation

50 In operation, let it be assumed that the operator's control lever 107 is initially in "Stop" position effecting operation of the ahead and astern valve devices 85 and 86 and of the start valve device 87 to open the respective pipes 47, 43 and 102 to atmosphere, and also effecting operation of the stop valve device 88 to supply fluid under pressure from the reservoir 101 to pipe 52. Fluid under pressure thus supplied to pipe 52 will move the double check valve 51 to its left hand position since pipe 50 is vented at this time as will be later brought out. With the double check valve 51 in its left-hand position pressure of fluid in pipe 52 will be effective through pipe 13 in the fuel cut-off device 10 to actuate piston 11 therein 55 to move the fuel control lever 7 to its cut-off position in which it is shown in the drawing. With the supply of fuel to the engine thus cut off the engine will be stopped.

Let it further be assumed that the engine was 70 last operated in the astern direction under which condition the power piston 37 will be positioned as shown in the drawing and the parts of the directional interlock valve device 45 will likewise be positioned as shown in the drawing. The astern pipe 43 connected to chamber 40 at one

side of the power piston 37 will therefore be open to atmosphere past the release valve 65 in the astern interlock valve device 56 of the directional control valve device 45, while the ahead control pipe 44 from chamber 41 at the opposite side of said piston will be open past the supply valve 57 in the astern interlock valve device 55 of the directional control valve device 45 to pipe 47 which is open to atmosphere through the operator's control valve device as above mentioned.

With the apparatus conditioned as just described, if the operator desires to operate the engine in the same direction as it was last operated, that is, in the astern direction in the present instance, he will move lever 107 from "Stop" position directly to the "Astern" "Start" position in the short slot 114. In this position of lever 107 cam 121 will act to close the release valve 99 and open the supply valve 90 in the astern valve device 86 so as to supply fluid under pressure to pipe 46 leading to the astern interlock valve device 56 in the directional control valve device 45, but the supply valve 57 in said interlock valve device will at this time be closed to prevent flow of fluid under pressure to pipe 43 and thus to chamber 40 in the fluid motor 35. The supply of fluid to chamber 40 at this time is not essential since the power piston 37 of the reversing motor 35 is already in the position for positioning the cam shaft 2 to provide for operation of the engine in the astern direction.

The movement of the operator's control lever 107 into the short slot 114 will also effect closure of the release valve 99 and opening of the supply valve 90 in the start valve device 87 so as to thereby supply fluid under pressure from the reservoir 101 to pipe 102 and thence to chamber 130 in the reversing interlock valve device 126. With the power piston 37 in its astern position as shown in the drawing the piston rod 38 will be positioned to effect closure of the release valve 137 and opening of the supply valve 131 in the reversing interlock valve device 126, so that fluid supplied to chamber 130 therein will promptly flow to pipe 23 and thence to chamber 30 in the starting air valve device 22, and also to chamber 77 in the directional control valve device 45.

Fluid pressure thus supplied to chamber 30 in the starting air valve device 22 will move piston 29 against spring 32 to close valve 27 and to open valve 26 against the opposing pressure of spring 33. With valve 26 open engine starting air from pipe 24 will then flow past said valve to pipe 25 and thence to the engine wherein it will act in the conventional manner to start the engine turning in the direction determined by the position of the cam shaft 2.

When the operator's control lever 107 is moved out of "Stop" position cam 122 will operate to permit closure of the supply valve 90 by spring 93 and opening of the release valve 99 by pressure of fluid from pipe 52, in the stop valve device 88, for thereby releasing fluid under pressure from pipe 52. At this time pipe 50 is also open to atmosphere by way of pipe 43 as above described, so that fluid under pressure will be released from chamber 12 in the fuel cut-off device 10 by way of pipe 52. Spring 17 in the fuel cut-off valve device will then actuate piston 41 to pull the fuel control lever 7 from its fuel cut-off position in which it is shown in the drawing, to the fuel supply position indicated by the dot and dash line 8. Fuel will thus be supplied to the engine so that when the engine starts to turn in the selected direction under the pressure of starting air sup-

plied by the starting air valve device 22 to pipe 25, the engine will fire and then run on fuel.

Fluid pressure supplied to pipe 23 for operating the starting air valve device 22, being also effective in chamber 77 in the directional interlock valve device 45 will actuate plunger 75 to move the disc 74 into frictional contact with the end of the crank shaft 1. When the crank shaft 1 starts to turn under the pressure of starting air supplied to the engine it will tend to turn the disc 74, but this tendency will be without effect in restarting the engine in its last direction of operation, since the parts of the directional control valve device will already be properly positioned from the last time the engine was operated, and will be maintained in this position by the power exerted by spring 79.

After the engine is started and running on fuel the operator will then move control lever 107 out of the "Astern" "Start" position into the adjacent "Run" position to thereby actuate plunger 104 and lever 117 to permit spring 93 to close the supply valve 90 in the start valve device 87 and to permit pressure of fluid in chamber 91 in said device to unseat the respective release valve 99, whereupon fluid under pressure will be released from piston chamber 30 in the starting air valve device 22 and from chamber 77 in the directional control valve device 45 by way of pipe 23 past the supply valve 131 in the reversing interlock valve device 126 and then through pipe 102. Spring 32 in the starting air valve device 22 will then return the piston 29 to the position shown in the drawing for opening the release valve 27 and during such operation spring 33 will close the supply valve 26 for thereby cutting off the supply of starting air to pipe 25 and to the engine and for opening said pipe to atmosphere past valve 27 and thence through port 28. Upon release of fluid under pressure from chamber 77 in the directional control device 45 pressure between the friction disc 74 and the end of the crank shaft 1 will be relieved so that said disc may free itself from said crank shaft, but the parts of the directional control device will remain in the position to which they were moved, that is, in the position shown in the drawing in the present instance, due to the action of spring 79 on the controlling lever 70. It will be noted that with the parts of the direction control device in the position just mentioned communication will be open between the ahead control pipes 41 and 44, while communication will still be broken between the astern control pipes 43 and 46, and pipe 43 will be open to atmosphere past the release valve 65 in the astern interlock valve device 56.

From the above description it will be noted that restarting the engine in its last direction of operation essentially consists of merely releasing fluid under pressure from the fuel cut-off device 10 by way of pipe 52 to permit supply of fuel to the engine, and of supplying fluid under pressure to actuate the starting air valve device 22 to supply starting air to the engine to cause the engine to start turning in the selected direction. Immediately upon firing of the engine, the lever is then returned to the "Run" position to cut off the supply of starting air to the engine, and the engine will then continue to run on fuel.

With the engine operating in the astern direction if the operator desires to reverse its direction of operation, that is, from astern to ahead, he will move lever 107 from the "Astern" "Run" position to the "Ahead" "Run" position and then,

if he desires, immediately to the "Ahead" "Start" position in slot 113.

Movement of the operator's control lever from the "Astern" "Run" position to the "Ahead" "Run" position will cause operation of the astern valve device 86 to open pipe 46 to atmosphere, without effect however since said pipe is merely open to chamber 59 between plunger 62 and the closed supply valve 57 in the astern interlock valve device 56 in the directional control valve device 45, and at the same time said movement of the operator's control lever will also effect operation of the ahead valve device 85 to supply fluid under pressure to pipe 47. Fluid thus supplied to pipe 47 will flow past the open supply valve 57 in the ahead interlock valve device 55 in the directional control device 45 to pipe 44 leading to pressure chamber 41 at the left-hand side of the power piston 37 and also leading to the double check valve 49.

Since pipe 43 is at this time open to atmosphere through the directional control valve device 45, the pressure of fluid provided in pipe 44 as just described will shift the double check valve 49 to its right hand position and then become effective in pipe 50 on the double check valve 51. Pipe 52 is open to atmosphere through the stop valve device 88 in the operator's control valve device with the lever 107 out of "Stop" position, so that pressure of fluid in pipe 50 will shift the double check valve 51 to its right hand position and then become effective through pipe 13 in the fuel cut-off valve device 10 and actuate said device to move the fuel control lever 7 to its fuel cut-off position to cut-off the supply of fuel to the engine, so that the engine may stop.

At the same time as the fuel to the engine is cut-off the pressure of fluid provided through pipe 44 in chamber 41 of the reversing motor 36 will move piston 37 from its astern position shown in the drawing to its ahead position at the opposite end of the cylinder 36 and this movement of said piston will move the control lever 5 to the ahead position indicated by the dot and dash line 5a for thereby shifting the cam shaft 2 to the position to provide for operation of the engine in the ahead direction.

With lever 107 in the "Ahead" "Start" position the start valve device 87 will act to supply fluid under pressure to pipe 102 leading to the reversing interlock valve device 126. As soon as the piston 37 starts moving out of its astern position shown in the drawing toward the opposite end of cylinder 36, the ball 139 will move into recess 142 to permit spring 132 to close the supply valve 131 in the reversing interlock valve device 126 so that fluid supplied to pipe 102 cannot flow to the starting pipe 23. However as soon as the power piston 37 obtains its ahead position at the right hand end of cylinder 36 the ball 139 will be moved out of the slot 142 to thereby close the release valve 137 and open the supply valve 131 in the reversing interlock valve device 126, so that fluid may then flow from pipe 102 to the starting control pipe 23 and thence to piston chamber 30 in the starting valve device 22 and also to chamber 77 in the directional interlock valve device 45.

The pressure of fluid thus provided in chamber 30 in the starting air valve device will then actuate said device to supply starting air from pipe 24 to pipe 25 and thence to the engine. If the engine is still turning in the astern direction after the cam shaft 2 has been moved to its ahead position and at the time starting air is supplied to pipe 25, such air will, as well known, be-

come effective in the engine to oppose movement of the engine pistons to thereby promptly bring the engine to a stop, then at the instant of stopping said air will be effective to start the engine turning in the new or ahead direction.

At the same time as the starting air is supplied to pipe 25 to start the engine, the pressure of fluid effective in chamber 77 on piston 75 in the directional control valve device 45 will move the disc 74 into frictional contact with the end of the crank shaft 1. With the crank shaft 1 still turning in the astern direction the disc 74 will have no effect upon the position of the parts of the directional control valve device 45 but immediately upon starting of the engine to turn in the new or ahead direction, as determined by the position of the cam shaft 2, the friction disc 74 will turn with the crank shaft 1 in a clockwise direction as viewed in Fig. 5 of the drawing. This turning of friction disc 74 in a clockwise direction will turn lever 70 in a counterclockwise direction which will permit spring 60 to close the supply valve 57 and pressure of fluid from pipe 44 in chamber 58 to open the release valve 65 in the ahead interlock valve device 55, so as to thereby release fluid under pressure from the power piston chamber 41 through pipe 44 and at the same time from chamber 12 in the fuel cut-off valve device 10 past the check valves 51 and 49 and through said pipe. Spring 17 in the fuel cut-off device will then rock lever 7 from its fuel cut-off position to its fuel supply position indicated by the dot and dash line 8, to thereby supply fuel to the engine. With the engine turning under the pressure of starting air supplied by the starting air valve device 22 the engine will then fire and run on fuel.

When the ahead interlock valve device 55 is operated to release fluid under pressure from the power piston chamber 41 and from the fuel cut-off device 10 as just described, the lever 70 acts to seat the release valve 65 and to open the supply valve 57 in the astern interlock valve device 56 to thereby reestablish communication between pipes 46 and 43. The opening of this communication is without effect at this time but is essential to subsequently reverse the direction of operation of the engine from ahead to astern, as will be later brought out.

After the engine is running on fuel in the ahead direction the operator will move lever 107 from the "Ahead" "Start" position in slot 113 to the adjacent "Run" position to thereby effect operation of the starting valve device 87 to open pipe 102 to atmosphere. Fluid under pressure will then be released from piston chamber 30 in the starting air valve device 22 and from chamber 77 in the directional control valve device 45 by way of pipe 23 and thence past the supply valve 131 in the reversing interlock valve device 126 and through pipe 102. Upon this release of fluid under pressure from chamber 30, spring 32 in the starting air valve device 22 will open the release valve 27 and permit closure of the supply valve 26 by spring 33 whereupon the starting air pipe 25 will be vented to atmosphere through the atmospheric port 28. The release of fluid pressure from chamber 77 will permit the friction disc 74 to disengage itself from the end of the crank shaft 1, but the parts of the directional control device 45 will remain in the position to which they were moved by said disc upon starting of the engine in the ahead direction, due to the over-center action of spring 79 on the lever 70.

To summarize, it will now be seen that if the operator moves the control lever 107 from the

"Astern" "Run" position to the "Ahead" "Start" position the fuel control device 10 will be promptly operated to cut off the supply of fuel to the engine in order that the engine may stop, and at the same time the reversing motor 35 will be operated to reverse the cam shaft 2 to provide for operation of the engine in the ahead direction. This reversing of the cam shaft 2 may be completed while the engine is still turning in the astern direction, but as soon as the cam shaft shifting has been completed starting air will be supplied to the engine by operation of the starting air valve device 22 to effect braking of the engine, in case it is not already stopped, and to effect starting of the engine in the new direction after it has come to a stop. The directional interlock device 45 will prevent operation of the fuel control valve device 10 to supply fuel to the engine while the engine is still turning in the direction of last operation, but immediately upon starting of the engine in the new or ahead direction, as in the present instance, said device will automatically operate to supply fuel to the engine so that it may fire and run on fuel. Then after the engine is running on fuel, the operator will move lever 107 to the adjacent "Run" position for cutting off the supply of starting air to the engine.

It will also be noted that the directional control device 45 not only controls operation of the fuel cut off device 10 to prevent supply of fuel to the motor until after the engine actually starts turning in the selected direction, but it also controls the supply of air for effecting movement of the reversing piston 37, so that after the reversing movement of said piston has been completed the actuating pressure in chamber 41 will be released in order to relieve piston 37 of such pressure during operation of the engine.

With the engine operating in the ahead direction if the operator desires to reverse the direction of operation to astern he will move lever 107 from the "Ahead" "Run" position to the "Astern" "Start" position in slot 114 and this operation will effect operation of the ahead valve device 85 to open pipe 41 to atmosphere and at the same time will actuate the astern valve device 86 to supply fluid under pressure to pipe 46. Fluid thus supplied to pipe 46 will flow past the open supply valve 57 in the astern valve device 56 of the directional interlock valve device 45 to pipe 43 leading to piston chamber 40 in the reversing motor 35 and also leading to the right-hand end of the double check valve 49. Since pipe 46 is at this time open to atmosphere through the directional control device 45, pressure of fluid supplied to pipe 43 will shift the double check valve 49 to its left hand position and then become effective in pipe 50. Pipe 52 is also open to atmosphere at this time so that fluid under pressure supplied to pipe 50 will move the double check valve 51 to its right-hand position and then flow through pipe 13 to the fuel cut-off valve device 10 and effect operation thereof to cut off the supply of fuel to the engine so that the engine may stop.

Since chamber 41 in the reversing motor 35 is open to atmosphere at this time through pipe 44 and past valve 55 in the astern interlock valve device 55 in the directional interlock valve device 45, fluid under pressure supplied through pipe 43 to chamber 40 in said motor will then move the reversing piston 37 from its ahead position at the right-hand end of cylinder 36 to its astern position at the left-hand end for thereby mov-

ing the cam shaft 2 to its astern position in which it is shown in the drawing.

With the operator's control lever in the "Astern" "Start" position in slot 114 the start valve device 87 will supply fluid under pressure to pipe 102, but the reversing interlock valve device 126 will operate during the reversing movement of the power piston 37 to prevent flow of fluid under pressure from pipe 102 to pipe 23. 5 When the reversing piston 37 attains its astern position in which it is shown in the drawing, the reversing interlock valve device 126 will be operated however to reestablish communication between pipes 102 and 23 so that fluid under pressure will then flow to the starting air valve device 22 to effect operation thereof to supply starting air to pipe 25 and thence to the engine. If the engine is still turning in the direction of last operation this supply of starting air will become effective in the engine to brake same and promptly bring it to a stop and then immediately be effective to start the engine turning in the new or astern direction determined by the new position of the engine cam shaft 2. Fluid 10 supplied to pipe 23 will also flow to chamber 77 in the directional interlock valve device 45 and therein act on piston 75 to move the disc 74 into frictional engagement with the end of the crank-shaft 1. If the engine is still operating in its last 15 direction of operation, that is, in the ahead direction in the present instance, the disc 74 will not change the position of the directional control device 45, but as soon as the engine starts to turn in the opposite or new direction determined by the new position of the cam shaft 2, the disc 74 will operate to turn lever 70 to the astern position shown in Fig. 5 of the drawing, to thereby permit closure of the supply valve 57 by spring 60 and opening of the release valve 65 20 by pressure of fluid from chamber 58 in the astern interlock valve device 56. Fluid under pressure will then be released from pipe 43 and thereby from the fuel control valve device 10 to permit operation thereof to draw the fuel control lever 7 from its fuel cut-off position to its fuel supply position indicated by the dot and dash line 8 for thereby supplying fuel to the engine. The engine will then fire and run on fuel. At the same time as fluid is released from the fuel cut-off device 10 by way of pipe 43, fluid 25 pressure will also be released from pressure chamber 40 in the reversing motor by way of said pipe so as to relieve the reversing piston 37 of actuating pressure after its operation has been completed.

After the engine fires and is running on fuel in the astern direction as just described, the operator will then move lever 107 out of the "Astern" "Start" position to the adjacent "Run" position to thereby effect operation of the start valve device 87 to open pipe 102 to atmosphere. Fluid under pressure will then be released from piston chamber 30 in the starting valve device 22 to permit closure of the supply valve 25 and opening of the release valve 27 30 therein. With the release valve 27 thus open fluid will be released from the starting air pipe 25. This release of fluid under pressure from pipe 23 will also result in a release of fluid under pressure from piston chamber 77, so that the disc 74 may disengage itself from the crank shaft 1. The parts of the directional control valve device 45 will however remain in their astern position 35 as shown in Fig. 5 under the action of spring 79

and in which position it will be noted that the release valve 65 is seated and the supply valve 57 open in the astern valve device 55 to thereby establish communication between pipes 47 and 44 as required to effect a subsequent reversal of the engine from operation in the astern direction to the ahead direction.

Whenever the operator desires to stop the engine, regardless of its direction of operation, he need only move lever 107 to "Stop" position for effecting operation of the stop valve device 88 to supply fluid under pressure from the reservoir 101 to pipe 52. With pipe 56 open to atmosphere by way of the directional control valve device 45 through either pipe 44 or pipe 43, as is always the case with the engine running, the pressure of fluid in pipe 52 will shift the double check valve 51 to its left-hand position and then become effective through pipe 13 in the fuel cut-off device 10 to actuate said device to move the fuel control lever 7 to its fuel cut-off position. When the supply of fuel to the engine is thus cut off the engine will stop.

When the engine is stopped from operation in an ahead direction the restarting of the engine in the same direction may be accomplished by operating the apparatus in a manner which will be apparent from the above description.

Summary

It will now be seen that I have provided a control apparatus for controlling the starting, stopping and reversing of a reversible internal combustion engine which is relatively simple. Reversal of the engine is effected by fluid under pressure supplied through a control pipe to a reversing motor and fluid pressure from this same pipe is employed for cutting off the supply of fuel to the engine so that immediately upon initiating a reversal in direction of operation of the engine the fuel supply to the engine will cut off in order to allow the engine to stop. A device responsive to direction of rotation of a rotatable part of the engine controls the supply of fluid under pressure to effect cutting off the fuel supply to the engine and is operable automatically upon starting of the engine to turn in the direction determined by the position of the cam shaft to promptly resupply fuel to the engine to permit restarting thereof in the new direction, but said device is operable to prevent resupply of fuel to the engine until after it does actually start turning in said new direction. The fluid pressure for actuating the reversing motor for effecting reversal of the cam shaft may also be controlled through the directional control device in which case said motor will automatically be relieved of actuating fluid pressure after the cam shaft has been shifted to the desired position.

Having now described my invention, what I claim as new and desire to secure by Letters Patent, is:

1. In fuel control apparatus for a reversible engine having a part rotatable in the direction of operation of said engine, the combination with reversing means operable to condition said engine for operation either in one direction or in the opposite direction, starting means operable to initiate turning of said engine, fuel control means operable to either cut off the supply of fuel to said engine or to permit supply of fuel to said engine, and operator's control means operable to effect operation of said reversing means, said starting means and of said fuel control means to cut off the supply of fuel to said engine,

5 of control means cooperative with said operator's control device to effect operation of said fuel control means to cut off the supply of fuel to said engine upon operation of said operator's control device to effect operation of said reversing means, and means adapted to cooperate with said rotatable part of said engine upon starting of said engine in a direction determined by said reversing means to operate said control means to effect operation of said fuel control means to permit supply of fuel to said engine.

2. In fuel control apparatus for a reversible engine having a part rotatable in the direction of operation of said engine, the combination with reversing means operable to condition said engine for operation in a reverse direction, starting means operable to initiate operation of said engine in said reverse direction, fuel control means adapted to be operated by fluid under pressure to cut off the supply of fuel to said engine, means operable upon release of fluid under pressure from said fuel control means to permit supply of fuel to said engine, and an operator's control device operative to effect operation of said reversing means and starting means and also operative to supply fluid under pressure to said fuel control means, of valve means controlling communication through which the fluid pressure is supplied from said operator's control device to said fuel control means, and means controlled by said rotatable part of said engine and operable upon starting of said engine in the direction determined by said reversing means to effect operation of said valve means to close said communication and to release fluid under pressure from said fuel control means.

3. In fuel control apparatus for a reversible engine having a part rotatable in the direction of operation of said engine, the combination with reversing means operable to condition said engine for operation either in one direction or in the opposite direction, starting means operable to initiate operation of said engine in the direction determined by said reversing means, fuel control means operable by fluid under pressure to cut off the supply of fuel to said engine and operable upon release of fluid under pressure to permit supply of fuel to said engine, an operator's control device operable to effect operation of said reversing means and starting means and also operable to supply fluid under pressure to one pipe upon operation to effect operation of said reversing means to condition said engine for operation in said one direction and to a second pipe upon operation to effect operation of said reversing means to condition said engine for operation in said reverse direction, said operator's control device being also operable upon supplying fluid under pressure to either one of said pipes to open the other pipe to atmosphere, and a double check valve connecting both of said pipes to said fuel control means and operable upon supply of fluid under pressure to either one of said pipes when the other pipe is open to atmosphere to open communication between the pipe supplied with fluid under pressure and said fuel control means, of two valve devices one for controlling communication through each of said pipes and operative to either open said communication or to close same and open to atmosphere the portion of the respective pipe connected to said double check valve, actuating means selectively operable to actuate either one of said valve devices to open the said communication controlled thereby and to at the same time

actuate the other valve device to close the other communication, and means arranged to control said actuating means controlled by rotation of said rotatable part of said engine and operable upon rotation of said part in a direction contrary to the condition of said reversing means to effect operation of the said valve device in the one of said pipes supplied with fluid under pressure to open the communication through the last named pipe and operative upon rotation of said part in the direction determined by said reversing means to effect operation of the last named valve device to close the said communication controlled thereby.

4. In fuel control apparatus for a reversible engine having a part rotatable in the direction of operation of said engine, the combination with reversing means operable to condition said engine for operation in either one direction or in the reverse direction, starting means operable by fluid under pressure to initiate turning of said engine, fuel control means selectively operable to either cut off the supply of fuel to the said engine or to permit supply of fuel to said engine, and an operator's control valve device operable to effect operation of said reversing means to condition said engine for operation in either one direction or in the opposite direction and also operable to either supply fluid under pressure to said starting means or to release fluid under pressure from said starting means, of directional control means adapted to be controlled by said rotatable part of said engine and cooperable with said operator's control device to control said fuel control means and operable upon rotation of said part in a direction contrary to the condition of said reversing means to render said operator's control device effective to effect operation of said fuel control means to cut off the supply of fuel to said engine and operable upon rotation of said part in a direction corresponding to the condition of said reversing means to effect operation of said fuel control means to permit supply of fuel to said engine, and means operable by fluid under pressure supplied to effect operation of said starting means to render said directional control means responsive to rotation of said part.

5. In fuel control apparatus for a reversible engine having a part rotatable in the direction of operation of said engine, the combination with reversing means operable upon supply of fluid under pressure to one pipe when fluid under pressure is vented from a second pipe to condition said engine for operation in one direction, and operable upon supply of fluid under pressure to said second pipe when fluid under pressure is vented from said one pipe to condition said engine for operation in said opposite direction, starting means operable to effect starting of said engine, an operator's control device selectively operable to supply fluid under pressure to either one of said pipes and at the same time to vent the other pipe and effect operation of said starting means, and fuel control means operable by fluid under pressure to cut off the supply of fuel to said engine and operable upon release of fluid under pressure to permit supply of fuel to said engine, of valve means controlled by said rotatable part of said engine and operable upon operation of said engine in either said one direction or in the said opposite direction to establish communication for supplying fluid under pressure from either said second pipe or said one pipe, respectively, to said fuel control means and operable upon operation of said engine in the direction de-

termined by said reversing means to cut off the supply of fluid under pressure to said fuel control means and to release the fluid under pressure therefrom.

6. In fuel control apparatus for a reversible engine having a part rotatable in the direction of operation of said engine, the combination with reversing means movable to one position to condition said engine for operation in one direction and movable to a second position to condition said engine for operation in the opposite direction, starting means for said engine, an operator's control device comprising a control lever having first and second positions and being operable upon movement thereto to effect movement of said reversing means to respectively either its first position or its second position and to also effect operation of said starting means, and fuel control means for said engine having a fuel supply position and a fuel cut-off position, of directional control means adapted to respond to direction of rotation of said rotatable part of said engine and operable to a first position upon operation of said engine in said one direction and to a second position upon operation of said engine in said opposite direction, and bias means operable to maintain said directional control means in either its first or second position with said engine operating in either said one or opposite direction respectively, said operator's control device cooperating with said directional control means upon movement of said control lever to either its first or second position when said directional control device is in either its said second or said first position respectively, to effect operation of said fuel control means to its cut-off position, and said directional control means being operable in either its first or second position with said control lever in respectively either its first or second position to effect operation of said fuel control means to its fuel supply position.

7. In control apparatus for controlling the reversing of a reversible engine having a part rotatable in the direction of operation of said engine, the combination with a reversing motor operable upon supply of fluid under pressure to one chamber to condition said engine for operation in one direction and operable upon supply of fluid under pressure to a second chamber to condition said engine for operation in the reverse direction, and an operator's control device operable to supply fluid under pressure to said chambers, of valve means controlling communication between said chambers and said operator's control device, actuating means movable to one position to effect operation of said valve means to connect said one chamber to said operator's control device and to connect said second chamber to atmosphere and movable to a second position to effect operation of said valve means to connect said second chamber to said operator's control device and to connect said one chamber to atmosphere, and means responsive to rotation of said rotatable part of said engine for controlling the positioning of said actuating means and operable upon operation of said engine in a direction determined by said reversing means in response to pressure of fluid supplied to said one chamber to move said actuating means to said second position and in a direction determined by operation of said reversing means in response to pressure of fluid supplied to said second chamber to move said actuating means to said one position.

8. In apparatus for controlling the reversing of and fuel supply to a reversible engine, the com-

bination with reversing means operable upon supply of fluid under pressure to one pipe to condition said engine for operation in one direction and upon supply of fluid under pressure to a second pipe to condition said engine for operation in the opposite direction, fuel control means operable by fluid under pressure to cut off the supply of fuel to said engine and operable upon the release of such fluid pressure to supply fuel to said engine, valve means operable upon supply of fluid under pressure to either one of said pipes to open communication between that pipe and said fuel control means, and an operator's control device operable to selectively supply fluid under pressure to either one of said pipes and to effect operation of said starting means, of other valve means controlling communication between said operator's control device and said pipes and selectively operable to open communication between either one of said pipes and said operator's control device and at the same time to close communication between the other one of said pipes and said operator's control device and to open the last named pipe to atmosphere, and means ar-

ranged to respond to direction of operation of said engine and operable upon operation of said engine in said one direction to operate said other valve means to establish the communication between said second pipe and operator's control device and operable upon operation of said engine in said opposite direction to effect operation of said valve means to establish the communication between said first pipe and said operator's control device.
